CLAIM

The ornamental design for an ace-style bottle, as shown and described.

DESCRIPTION

FIG. 1 is a front elevated perspective view of an ace-style bottle, showing the new design;

FIG. 2 is a front view thereof;

FIG. 3 is a rear view thereof;

FIG. 4 is a side view thereof;

FIG. 5 is the opposite side view thereof;

FIG. 6 is a top view thereof; and,

FIG. 7 is a bottom view thereof.

In all figures, any showing of the environment and/or drawing disclosure by broken lines is for illustrative purposes only and forms no part of the claimed design.

1 Claim, 7 Drawing Sheets(56)
